[57] CLAIM

The ornamental design for a dispenser cap, as shown and described.

DESCRIPTION

FIG. 1 is a perspective view of a dispenser cap showing my new design, the broken lines showing a container being for illustrative purposes only;

FIG. 2 is a top plan view;

FIG. 3 is a side elevational view, the opposite side being the same in appearance;

FIG. 4 is a bottom plan view;

FIG. 5 is a top plan view showing the dispenser cap in an open position;

FIG. 6 is a bottom plan view showing the dispenser cap in an open position; and

FIG. 7 is an exploded perspective view thereof.
